TURN SHOE AND METHOD FOR MAKING
SAME

John Trusler, Bloomfield, N. J., assignor of one-half to L. W. Proctor, Brooklyn, N. Y.

Application March 3, 1933. Serial No. 659,545

3 Claims. (Cl. 12—142)

The present invention relates to improvements in turn shoes and methods for making same.

The turn shoe is constructed with a single sole which is shouldered and tacked on the last flesh side up. The upper is then lasted wrong side out and sewed to the free portion of the sole, which portion is usually called the sewing rib or lip. The last is then removed and the upper and sole turned inside out; following which, the last is again put back into the shoe, and the shoe is finished.

This process leaves a ridge all around the shoe on the inside where the upper is attached to the sewing rib and is the greatest disadvantage of this type of construction as it reduces the amount of space inside the shoe on which the foot has an uninterrupted flat surface to tread.

It is the purpose of the present invention to eliminate this ridge and provide a continuously flat surface on the inside of the shoe.

It is another object of the invention to produce a turn shoe having the above described advantage by simple steps of a method which adds very little, if any, manufacturing expense to present shoe factory procedure, and which may be taught experienced shoemakers in a very short time.

With the foregoing and other objects in view, the invention will be more fully described hereinafter, and will be more particularly pointed out in the claims appended hereto.

In the drawings, wherein like symbols refer to like or corresponding parts throughout the several views,

Figure 1 is a perspective view showing an improved sole constructed in accordance with the present invention with the flesh side up and the flap thrown back.

Figure 2 is a similar view with parts broken away and showing the flap restored to normal position covering the shouldered portion.

Figure 3 is also a perspective view showing the improved sole grain side up.

Figure 4 is a longitudinal section taken on the line 4—4 in Figure 1.

Figure 5 is a transverse section taken on the line 5—5 also in Figure 1.

Figure 6 is a top plan view with parts broken away showing the improved sole on the last with the upper sewed thereto.

Figure 7 is a cross section taken on the line 7—7 in Figure 6 with the last removed.

Figure 8 is a view similar to Figure 7 after the

shoe has been removed from the last and turned inside out.

Figure 9 is a fragmentary cross section through a corner portion of Figure 8 taken on an enlarged scale and on the line 9—9 in Figure 10, and

Figure 10 is a longitudinal sectional view taken through a completed shoe constructed according to the present invention.

Referring more particularly to the drawings, 12 designates the flesh side and 13 the grain side of a leather sole such as used in turn shoes. Ordinarily a shouldered portion 14 is made on the flesh side of the sole outwardly of a sewing rib or lip 15. When the sole is put on a last flesh side up the upper is placed on a last inside out with the edges of the upper engaging the shouldered portion 14. Such edge of the upper is stitched to the sole by stitches passing through the sewing rib 15.

In accordance with the present invention the 75 sole on its flesh side is first cut all around the front portion from shank to shank and for an inch or so deep to provide a flap 16. This flap is preferably very thin and as before stated is cut on the flesh side of the sole.

As shown in Figure 1 the flap 16 is folded back or inwardly to expose the portion of the sole beneath such flap; and in this exposed portion is formed the shouldered portion 14^a and the 80 sewing rib 15^a.

Figure 5 shows the flap 16 folded back and in dotted lines the flap is shown as extending in its normal position whereby it covers the shouldered portion 14^a and the sewing rib 15^a.

The improved sole is prepared with a channel 90 knife, especially made, whereby to produce this flap 16, the flap being folded back as shown to expose the under surface of the flesh side of the sole for the production of the regular shouldered portion 14^a and sewing rib 15^a. The improved sole, in the condition shown in Figures 1, 4 and 5 is then placed upon a last, as indicated in Figures 6 and 7, with the flesh side out and with the flap 16 folded back to expose the shouldered portion 14^a and the sewing rib 15^a. The upper 17 100 is then applied to the last in the usual manner inside out and its edge 18 brought over and against the shouldered portion 14^a, being sewed to the sole by the stitches 19 passing through the sewing rib 15^a.

After the shoe is lasted and sewed, the flap 16 is put back in place, as indicated in Figures 6 and 7, except in Figure 6 the tip is folded back for clearness of illustration. After this operation the shoe is removed from the last and turned in-

side out. In other words from the position shown in Figure 7 to that shown in Figures 8 and 9, thus bringing the thin flap 16 and the flesh side of the sole upon the inside of the shoe. The flap 5 covers the objectionable shouldered portion 14^a as well as the sewing rib 15^a and the stitches, and such flap 16 leaves a flat unobstructed surface extending all the way across the whole width of the sole on the inside, adding naturally to the 10 comfort of the wearer.

I am aware that some factories have proposed to put a sole leather skiver inside the shoe and under the sock lining to accomplish the same result, but this fills up the space inside the shoe 15 and does not leave as much room as the present construction and method, but such prior method requires the purchase and use of a larger shoe than the foot would ordinarily require. Such requirement is commercially objectionable, especially in women's shoes where the purchaser desires the smallest size that can be possibly worn. 20

I am also aware that it has been proposed to split soles in a somewhat similar fashion but for an entirely different purpose, as shown and described for instance in the Lifschutz Patent No. 1,795,222 dated March 3, 1931, in which the flap 11 is made on the grain side and not on the flesh side, but this is not a turn shoe and the flap 11 is on the outside of the finished shoe, thus taking 30 the wear and necessarily being very thick and in any event requiring early repair and on account of the thickness of flap making it difficult to expose the channel for sewing and lasting.

In Figures 9 and 10 there is shown an insole 20 in the finished shoe which insole is usual in these types of shoes.

In Figures 3 and 10 there is shown a heel flap 21 cut from the grain part of the sole which is also a usual construction.

It is obvious that various changes and modifications may be made in the details of construction and design of the above specifically described embodiment of this invention without departing from the spirit thereof, such changes and modifications being restricted only by the scope of the following claims.

What is claimed is:—

1. An improved turn shoe comprising a sole having a shouldered portion and sewing rib, an upper having its edge inserted against said shouldered portion and stitched to said rib, and a thin flexible flap cut from the sole from its outer edge all around from shank to shank at the forepart of the sole and extending inwardly of said rib and adapted to be folded down over said shouldered portion and rib and to form a continuous uninterrupted flat surface presented against the foot on which to tread. 80

2. The herein described method for forming turn shoes, which consists in supplying a sole having its flesh side split all the way around from shank to shank at the forepart of the sole to provide a thin flexible flap with the inner portion of the flap attached at the intermediate part of the sole, said sole having a shouldered portion and a sewing rib in the space beneath the flap, folding the flap inwardly to expose the shouldered portion and sewing rib, placing the edge of an upper against the shouldered portion and stitching said upper to the sewing rib, subsequently straightening said flap outwardly and cementing or otherwise securing the flap over the shouldered portion, rib and engaged edge of the upper, and turning the sole and upper so as to bring the thin flap inwardly of the shoe. 95

3. The herein described method for manufacturing turn shoes from a sole having its flesh side split to provide a very thin flap extending inwardly about an inch all the way around the forepart of the sole from shank to shank and having beneath the flap a shouldered portion and a sewing rib in the flesh portion, which consists in folding the flap inwardly upon the intermediate portion of the sole to reveal the shouldered portion and sewing rib, lasting the sole with the flesh part out, lasting an upper and bringing the edge of the upper against said shouldered portion, stitching such upper to the sewing rib, straightening out the flap to its original position over the shouldered portion and rib and securing the flap in place, removing the last and turning the shoe inside out whereby to bring the flap against the inside of the 120 foot.

JOHN TRUSLER.
